UNITED STATES PATENT OFFICE

ARDEN R. JOHNSON, OF ST. CHARLES, MISSOURI

TIMER FOR ELECTRIC CIRCUITS

Application filed January 6, 1928. Serial No. 244,825.

This invention relates to timers for electric circuits, and particularly to photographic print timers. It has for one of its objects providing means for automatically timing the length of time an electric circuit is to be closed. The particular application of the timer in this case is to the exposure of sensitized photographic sheets to the light of an electric lamp. The invention has for a further object providing means for enabling the operator to determine, by inspection, substantially the time of exposure necessary to produce the best results in printing photographs. Other objects of the invention will be apparent from a consideration of the accompanying drawings and the following description thereof.

Of the drawings, Fig. 1 is a front elevation of apparatus which embodies the features of my invention; Fig. 2 is an enlarged rear view of the apparatus with the rear side of the casing removed; Fig. 3 is a sectional view of the same along the line 3—3 of Fig. 2; and Fig. 4 is an enlarged sectional view along the line 4—4 of Fig. 3.

The operation of the timing apparatus which I provide depends primarily on the swinging of a pendulum which, as it swings, closes and opens an electric circuit and this, in turn, operates an electric light to which the sensitized photographic sheet is exposed. By suitable adjustments, the time during which the current is passed through the lamp can be controlled, and the time of exposure thus can be made as little or as much as may be desired.

The apparatus, for convenience, is mounted in a casing 5 in the upper portion of which is a horizontally mounted supporting rod 6. To this rod is rotatably suspended a pendulum rod 7, and a pendulum bob 8 is fixed to the lower end of the rod. The length of the pendulum rod may be whatever is convenient for the particular use, but I prefer, ordinarily, a rod which is about twelve inches long from its point of suspension to the center of the pendulum bob; and the bob, in this instance, has a diameter of about two inches. However, it is to be understood that these

dimensions are not an essential part of my invention.

The pendulum, as described, has a time of complete oscillation of about one second. Any convenient means may be provided for releasing the pendulum and for stopping it after each complete oscillation has been made. I prefer, for the purpose, a pawl 10 which is pivoted to the pendulum rod and which has a tooth 11 which is adapted to coact with a pin 12 fixed to a lever 13. This lever has its fulcrum 14 fixed to the side of the casing and it is resiliently held in the normal position indicated by a spring 15. Fixed to the fulcrum 14, preferably on the outside and on the front of the casing, is an operating arm 16. In order to release the pendulum the operator presses downwardly on the arm 16, a flange 17 being provided for this purpose. This rotates the lever 13 so as to carry the lower end to the right and bring the inclined surface 20 of the pawl against a projection 21, so that the pawl is forced upwardly with reference to the pin 12 and is released from coaction with the pin. This releases the pendulum and allows it to oscillate. But, ordinarily, as soon as the pendulum is released, the operator releases the arm 16 and the spring 15 forces the arm upwardly against a stop 28 and the lower end of the lever 13 is again brought back to normal position so that the pawl 10 again coacts with the pin 12 as soon as the pendulum has made a complete oscillation. The inclined surface 20, coacting with the pin 12, raises the pawl upwardly as the pendulum returns until the pin passes off from the surface and is caught by the tooth 11.

The lamp 54 is used, as hereinafter described, for printing the photographs, and the means for controlling the light of the lamp comprise an electric circuit consisting of the wires 23 and 24. The wire 23 passes to the lamp 54 in the ordinary manner and the wire 24 passes to any suitable source of electric supply 25 and thence, by the wire 26, to the lamp. The wire 23 is electrically connected to a switch terminal 27 which is fixed to an arm 30. The arm 30 is rotatably mounted in any suitable manner. In this instance,

I prefer to suspend it rotatably on the rod 6. A second electric terminal 31 is mounted on, but insulated from the pendulum rod 7 and the wire 24 is electrically connected with this terminal.

In operation, when the pendulum is released at some predetermined time during the oscillation, the terminal 31 will come in contact with the terminal 27 and the lamp circuit will be closed. As the arm 30 is rotatably mounted, when the contact occurs the arm will be carried with the pendulum rod, but, on the return, the rod 30 will stop at its normally adjusted position, as hereinafter described, and the contact between the terminals will be broken. Hence, the lamp will be operated only during that portion of the complete oscillation that the two switch terminals are in contact.

20 In order to adjust the time of operation of the lamp, means are provided for varying at will the position of the contact 27. I prefer, for this purpose, an arm 32, also rotatably mounted on the rod 6 but rigidly fixed to 25 the arm 30 so that the position of the arm 30 can be controlled by the position of the arm 32. The arm 32 crosses a slot 33 in the casing. Passing through this slot and under the arm 32, thus suspending the arm, is a 30 flange 34 fixed to another arm 35 outside of the casing. The arm 35 is fixed to a segmental member 36 which is rotatably suspended by the rod 6, or in any other suitable manner. Obviously, by varying the position of 35 the member 36, the position of the rod 30 and, hence, of the contact 27, will be varied.

The lower edge of the segmental member 36 passes adjacent a pointer 37, which is fixed to the arm 16, and a suitable scale 40 coacts 40 with the pointer 37 so as to indicate the position of the arms 35 and 32 and, hence, of the contact 27. The arrangement is such that, when the pointer 37 points to the one-second mark of the scale 40, the terminals 27 45 and 31 will be relatively positioned so that they will be in contact for one second during the swing of the pendulum. Or, if the pointer points to the line 41, the terminals will be in contact for half a second. Hence, by 50 positioning the pointer with reference to the scale between the zero line and the one second line, the fraction of a second of time desired to operate the lamp will be obtained.

If it is desired to operate the lamp more 55 than one second with the apparatus described herewith, the operator can hold the arm 16 down and the pendulum will then make two complete oscillations, or as many complete oscillations as may be desired. However, if 60 several oscillations are required, it may be necessary for the operator to release the arm after two or three oscillations so as to give the pendulum an additional impulse. It will be understood that in increasing the 65 length of time beyond one second, any addi-

tional fraction of a second may be obtained by suitably adjusting the position of the contact 27. For instance, if a second and a half is required, the pointer would be set for about three-fourths of a second so that, during two oscillations, the total time that the lamp would be operated would be a second and a half.

70 Although there is some lag in the intensity of the light, after the closing of the terminals of the circuit, which affects the effect of the light on the sensitized paper, yet, ordinarily this is compensated for by the lag in the dying down of the light when the contacts are broken. So that, for ordinary 75 lights at least, this lag is immaterial.

The particular application of my invention in this case is to the printing of photographs. In the operation of this device, for 80 this purpose, it is sometimes desirable to be able to estimate the time of exposure necessary with the particular negative used or for other reasons, and for this purpose I provide in the casing an opening 45 across which are mounted strips of selected negatives, comprising, in this instance, strips 46, 47 and 48. The negative 48 is more dense than the others and the negative 47 is more so than the negative 46. Back of this opening, I place a lamp 50. This lamp may be supported in any suitable 90 manner; for example, by means of a bracket 51, in the front of the opening 52 in the rear side of the casing. Obviously, the operator in front of the casing will be able to observe the effect of the lamp on the different negatives 46, 47 and 48, and the intensity of the light will vary with reference to the relative 95 densities of the negatives.

Any suitable means may be used for exposing the sensitized prints to the light when the timer is used for photographic purposes. I 100 prefer to use the following described apparatus. The printing lamp 54 is enclosed in a casing 53. Above the printing lamp is mounted a transparent plate 55 on which is placed the negative 56 and the sensitized paper 57, in any ordinary manner.

105 In determining the time of exposure desired, the operator places the negative on the plate 55 and compares the intensity of the light which reaches his eye through the negative with the intensity of the light passing through the negatives 46, 47 and 48. The exposure necessary for a particular negative 110 showing a light intensity which corresponds to the light intensity of one of the negatives 46, 47 and 48 will be the same as the time experimentally determined for that particular negative. For instance, if the time 115 experimentally determined for the particular negative is one second, and the light intensity through this negative, say 48, corresponds to the negative under test, the exposure of the sensitized sheet would be one second. In this manner, the operator can read- 120

ily determine the approximate time, and a little experience will indicate to him the exact time required for the exposure.

It will be obvious, that, having once set the apparatus for exposing a definite length of time, as many prints may be taken as may be desired without any resetting of the apparatus, as it is arranged to maintain any adjusted position indefinitely. For instance, although the member 36 is rotatably mounted in the rod 6, a spring 60 brings the segment firmly against the wall of the casing but yields sufficiently to allow suitable rotation of the segment for a new adjustment. By means of the nut 61, the compression of the spring may be made sufficiently great to prevent any misplacement of the segmental member by the operation of the device and, hence, when the apparatus is once set for a certain time, there will be no change which would tend to vary the time of the exposure.

I claim as my invention:

1. A timer comprising a pendulum adapted to open and close an electric circuit as it oscillates, means for oscillating said pendulum, said means comprising a pawl pivoted to said pendulum, a pivoted arm, a pin fixed to said arm and adapted to coact with said pawl when the pendulum is rotated to one side of a vertical line passing through its point of support, and means for releasing said pawl from coaction with said pin.

2. A timer comprising a pendulum adapted to open and close an electric circuit as it oscillates, means for oscillating said pendulum, said means comprising a pawl pivoted to said pendulum, a pivoted arm, a pin fixed to said arm and adapted to coact with said pawl when the pendulum is rotated to one side of a vertical line passing through its point of support, and means for releasing said pawl from coaction with said pin, said releasing means comprising means for moving said pin further away from said line, and means for releasing said pawl from said pin.

In testimony whereof, I hereunto set my hand.

ARDEN R. JOHNSON.
